COMBINATION FLASK AND CUP

Hiram G. McCarty, Cleveland, Ohio

Application June 5, 1936, Serial No. 83,613

2 Claims. (Cl. 215—10)

My invention relates to a combination flask and cup, and in particular to a flask, preferably of glass, having a cup removably mounted there-in.

5 One object is to provide a means whereby a cup or glass may be held within the neck of the flask without attachment thereto but in which nevertheless the flask will be sealed against leakage of its contents.

10 A further object is to provide a simple structure having a minimum of interlocking or screwed parts.

Further objects and advantages may be noted from the specification and its accompanying 15 illustrations, in which:

Fig. 1 is an elevation of the flask with the cap screwed on the neck.

Fig. 2 is an elevation of the flask with the cap removed.

20 Fig. 3 is a section on line 3—3 of Fig. 1 with the cup or glass mounted within the neck of the flask.

Fig. 4 is an enlarged sectional view of the cup or glass.

25 Fig. 5 is an enlarged sectional view of a modified form of the cup or glass.

Referring to the drawing: A hollow body 10 comprising a neck 11 has a flange 12 outwardly disposed therefrom centrally of said neck, and an 30 externally threaded portion 13 adjacent the flange 12 and toward the outer end of said neck 11.

A seat 14 within the body 10 has an opening 15 therethrough connecting the hollow interior 35 10a of the body 10 with the orifice 11a within the neck 11.

A resilient washer 16 is superimposed upon the seat 14 and a cup or glass 17 is inverted thereon; a second resilient washer 18 is superimposed 40 over the cup or glass 17 adjacent the annular flanged base 19 of the cup or glass 17, so that said resilient washer 18 is confined between the annular flanged base 19 of the cup or glass 17 and the top surface of the neck 11.

45 Another resilient washer 20 is mounted over

the neck 11 adjacent to and directly above the flange 12 on said neck 11 and a cap 21 is internally threaded at 22 and is screwed down upon the threaded portion 13 of the neck 11.

Thus when the flask is filled with liquid 23, the 5 cup or glass 17 is inverted and placed within the neck 11, seating upon the resilient washer 16 mounted on the seat 14 of the body 10. The cap 21 is then screwed down upon the threaded portion 13 of the neck 11, the resilient washers 16, 10 18 and 20 forming a triple seal for the liquid within the container.

A modified form of cup or glass 25 is shown in Fig. 5.

The material used for this structure is preferably of glass, but it may be made of any suitable material such as metals of different kinds, porcelain, or earthenware and it may be spun, cast, moulded or drawn; I do not desire to confine the details of my invention to the precise 20 structure shown but to elaborate and modify within the scope of the invention.

I claim:

1. The combination of a container having a neck provided with an internal seat and an external flange and thread, gaskets on the seat and the flange, an inverted cup fitting within the neck, with its rim resting on the gasket on the seat, and a cap screwed on the neck and against the gasket on the flange and bearing against the 30 base of the cup to press its rim against the gasket on the seat.

2. The combination of a container having a neck and an internal seat at the junction of the neck with the body of the container, the neck 35 having an external thread and a flange below said thread, an inverted removable cup fitting within the neck and having an enlarged base, a gasket confined between the rim of the cup and the seat, another gasket confined between the enlarged 40 base of the cup and the outer end of the neck, a cap screwed on the neck and against the base of the cup, and a gasket confined between the cap and the flange.

HIRAM G. McCARTY. 45
